DENTAL DEVICE

George M. Hollenback, Los Angeles, Calif.

Application March 12, 1937, Serial No. 130,426

3 Claims. (Cl. 32—56)

This invention relates to dental devices, and particularly to a novel form of pneumatic mallet useful for the purpose of driving and packing a filling material into an excavated hollow in carious teeth.

An object of the invention is the provision of a pneumatic mallet of compact size, being as small as the average hand-piece for a dental drill, and which may form a portion of the dentist's equipment generally carried adjacent the dental chair.

The invention is so arranged that the means for creating fluid reaction, to-wit, an air pump, may operate in conjunction with the mechanism that ordinarily operates in conjunction with the dental engine.

An object of the invention is to provide a simple mechanism of attractive appearance, small and unobtrusive, and which is efficient in operation.

As a brief outline of the practice of the invention, I have provided what I term a hand-piece incorporating a cylinder within which is a piston constituting a loosely moving hammer. This hammer is adapted to be driven against an anvil, which anvil in turn, through a suitable stem connection, is adapted to drive a plugger. The anvil carries a valve, and the end of the hand-piece opposite said anvil is provided with an adjustable valve. The pneumatic means for operating the hammer comprises a cylinder within which is reciprocated a piston. The cylinder communicates, through any suitable means such as a flexible hose of small cross section, with the adjustable valve in the hand-piece. Normally the valve carried by the anvil is closed to the atmosphere while the opposite valve may be adjusted as to its opening within the cylinder of the hand-piece. Hence, if the valve associated with the anvil is closed to the atmosphere, the piston will reciprocate to a slight extent within the cylinder in accordance with reciprocatory movement of the piston within the cylinder of the pump. When pressure is placed upon the end of the plugger, the valve associated with the anvil is open to an adjustable extent, dependent upon the pressure, with the result that when the pneumatic pump is actuated, pulsations of said pump are communicated to the piston or hammer within the cylinder and the said piston or hammer is driven forcibly against the anvil, thus causing a blow which is communicated directly to the plugger. The more pressure placed upon the end of the plugger, the greater the opening of the valve, with the result that the striking force between the hammer

and anvil becomes more definite and greater. This striking force is readily adjusted by the rate of speed of reciprocation of the pneumatic pump and likewise the degree of opening of the valve between the flexible hose and the cylinder of the hand-piece and pneumatic pump.

An object of the invention is the provision of a dental device of the character above outlined, which allows controlled pressure or striking force of the plugger against some object, such as the filling to be placed within a tooth.

Another object is the provision of a dental device adapted to condense a filling by either rapid or slow succession of strokes of the plugger and in accordance with the pressure placed upon the plugger.

Another object is the provision of a dental device of the character stated wherein a pneumatically operated plugger may be readily controlled as to its striking force by suitable adjustments convenient to the operator of the device.

In the drawing:

Figure 1 is an illustration of the dental tool, the plugger member of which is engaging a packing or filling in a carious tooth, together with a pump interconnected with said dental tool through the medium of a flexible member, such as a rubber tube.

Figure 2 is a fragmentary longitudinal sectional view of one form of dental tool incorporating the invention.

Figure 3 is a fragmentary longitudinal sectional view of a second form of dental tool having a contra-angled head piece.

Figure 4 is a cross sectional view on the line 4—4 of Figure 2, and,

Figure 5 is a cross sectional view on the line 5—5 of Figure 2.

Referring now to the drawing, I have shown in Figure 1 a pneumatic mallet 1, a pump 2, and a flexible hose 3 between the pump and the pneumatic mallet. The pump shown at 2 is simple in design and is adapted for attachment to the bracket adjacent the dental engine. The bracket is shown at 4 and the pump which comprises a cylinder 5 is adapted to house a piston 6 reciprocated by a pulley wheel 7. The pulley wheel 7 is provided with a central shaft having a crank arm to which the piston arm 8 is secured. One end of the cylinder is secured to a member 9, which member in turn has secured thereto a stud 10 carrying a set screw 11. This stud is transversely bored whereby the bracket 4 may be passed through said bore, the device being locked in position by turning the set screw 11. To drive

the pulley wheel, I have provided a resilient belt 12, such as generally employed in conjunction with a dental engine, and this belt is received within the groove of the pulley wheel and the 5 groove in the wheel secured to the shaft of the dental engine, the dental engine not being shown. This comprises the pump in its simplest embodiment and a pump of this character has been found to be very efficient in use and practically 10 noiseless in operation. In fact, the pump shown in the drawing is substantially the normal size thereof.

The pneumatic mallet is of two forms, that shown in Figures 1 and 2, and the form shown in Figure 3. The principle of operation of all the 15 mallets, however, is identical.

Referring to Figure 2, the mallet includes an elongated hand-piece 13 having a bore 14 of uniform diameter and a screw-threaded counter-bore 15 of greater diameter than the bore 14. This counter-bore extends inwardly from one end of the hand-piece. The bore 14 constitutes a cylinder within which is a loose piston or hammer 16. This piston is adapted to be reciprocated 25 within the cylinder when the pneumatic pump shown in Figure 1 is operated. One end of the hand-piece is adapted to detachably receive a valve assembly designated generally by 17. As shown in Figure 1, the hand-piece is formed with 30 a bayonet slot 18 and the valve assembly is provided with a pin 19 for reception in said bayonet slot to lock said assembly within said hand-piece. This valve assembly includes two members 20 and 21. The member 20 has a shank 22 provided 35 with a bore 23 and a concentric threaded counter-bore 24. Between the counter-bore and the bore 23 is a tapered wall 25 constituting a valve seat. One end of the shank is provided with a member of enlarged diameter 26, the periphery 40 of which is knurled, as shown at 26' in Figure 1. This member 26 is a hand-piece which permits the insertion of the shank 22 within the bore of the cylinder and in such a manner as to permit locking engagement of the pin 19 carried by 45 the shank within the bayonet slot 18. The second member 21 of the valve assembly includes an enlargement 27 having a serrated periphery 28, and extending from opposite sides of said enlargement are members 29 and 30. The member 50 29 is a nipple adapted to receive a portion of one end of the hose 3. The member 30 is provided with a threaded periphery 31 for threaded engagement with the threads 24 and this member 30 is provided with a reduced conical end 55 32 constituting a valve. The member 30 is provided with a transverse bore 33 inward of the head 32 and an axial bore 34 communicates with the transverse bore 33 and through the members 30, 27 and 29. It is to be noted that the diameter 60 of the threaded portion of the member 30 is greater than that portion having the valve head and the transverse bore 33. It is apparent that relative opening between the valve head and the valve seat is accomplished by rotating the member 21 relative to the member 20 as the two members are in threaded engagement. For the purpose of regulating the opening and maintaining 65 said regulation, a spring finger 35 is secured to the member 17 and is adapted to engage serrations in the member 27.

The end opposite the hand-piece adapted to receive the valve assembly has secured thereto means whereby blows may be delivered to a plugger. The means generally is designated by 70 the numeral 36. The said means includes a nose

37 reduced and threaded at one end 38 for threaded engagement with the threads 15 of the hand-piece. This nose piece is provided with a cylindrical central bore 39 and an oval cross sectional bore 40, both bores being in communication. The nose is likewise provided with one or more diametric ports 41 extending between the periphery of the said nose and the bore 39. Within the said nose is confined an expansion or elastic tubular chuck 42. This chuck is of that type 10 provided with longitudinally extending slots, as illustrated in dotted lines at 43, to the end that any member received within the confines of the chuck is yieldingly held therein. Secured in part within the chuck and extending beyond the inner 15 end 44 thereof is a valve stem or shank 45. That portion of the valve stem or shank within the chuck is provided with a half-round notch 46 and the said valve stem is secured to the chuck in the position illustrated in Figure 2 through the 20 medium of a pin or other device, as illustrated at 47. Adapted for reception within the counter-bore 15 and of lesser diameter than the said counter-bore is a valve 48 constituting a disc. This valve disc is pinned at 49 to a reduced diameter portion 50 of the stem or shank 45. It will thus be seen that the end 51 of the nose acts as a valve seat for the valve 48 to prevent rotation of the valve and its stem or shank, and a pin 52 is transversely passed through the said disc and 30 received within an eccentric bore 53 of the nose. The two bores of different diameter within the nose provide an annular shoulder 54 and a coil spring 55 surrounding said stem or shank 52 has one end in engagement with the shoulder 54 and 35 the opposite end engaging an end of the chuck 42.

What are known as pluggers may be utilized with the present invention and a type of plugger is shown at 56. This plugger is provided with a 40 condensing point 57 and the shank thereof at its end is provided with a half-round notch 58 adapted to cooperate with the like half-round notch 46 of the stem.

It is to be noted that the bore 40, which is oval 45 in cross section, provides a support for one end of the stem 52, see Figure 5, and a pair of longitudinally extending ports included between the stem and the said bore.

In an adaptation of that form of the invention 50 shown in Figure 2, I have provided within the cylinder 14 and adjacent one end of the shank 22 a coil spring 59.

That form of the invention illustrated in Figure 3 does not differ in essential details from that shown in Figure 2, with the possible exception that the form shown in Figure 3 is adapted to operate with a contra-angle portion. The hand-piece 13 is provided as before, one end of which is formed with a threaded counter-bore 15. A 55 coupling 60 has a central bore 61 and a bore 62 oval-shaped in cross section. This coupling is reduced in diameter and externally screw-threaded as shown at 63 for threaded engagement with the threads 15. The opposite end of the 60 coupling is provided with an internally threaded portion 64. Transverse ports 65 extend between the periphery of the coupling and the bore 61. The nose 66, in the present instance, includes two angularly related portions 67 and 68, the 65 part 68 terminating at one end in a reduced diameter externally threaded portion 69 for threaded engagement with the threads 64 of the coupling. This portion 66 is likewise formed with a longitudinally extending bore, which merges with 70 75

a bore in the part 67. The part 67 is internally threaded at 70 to receive a nut 71. This nut is provided with an elastic extension or shank 72 and the ends of said extension are inturned or bent inwardly, as shown at 73. Within the confines of the threaded bore 15 is a valve 74 constituting a disc pinned to a stem 75, as shown at 76. The valve seat is shown at 77, the seat being an end of the coupling 60. This stem 75 is received within the bore of the portion 66 of the nose and is provided with an enlarged head 78 having a concavity in the end thereof. Adapted for placement against the concavity of the head and within the portion 67 are balls 79 and 80. Surrounding the stem and within the bores of both the coupling and the nose is a coil spring 81. One end of said spring bears against the head 78 and the opposite end against a shoulder defined by the central bore of the nose and the bores 62. The tendency of this spring is to at all times urge the valve to seated position.

The plugger 82 has its shank 82' provided with an annular slot 83. Thus, when the shank of the plugger is forced within the confines of the 25 silent extension of the nut, the inwardly directed ends of said extension may be received within the annular groove of the plugger shank. It will be noted that the plugger shank extends through the nut and adjacent the ball 80.

30 The invention in either of its forms constitutes a pneumatic mallet of small size, particularly adapted for dental use for the purpose of packing and condensing gold, or other filling material, in the filling of teeth and which strikes direct and 35 very rapid blows adjustable as to force and either continuous or dependent upon touch, the blow being given by the plugger upon the filling material when the condensing point of the plugger is pressed upon the filling and ceasing when the 40 pressure is removed. The force of the blow delivered by the plugger is also dependent, in addition to pressure thereagainst, upon certain adjustments to the end that the minimum or maximum blow to be delivered may be regulated to meet any 45 existing condition desired by its operator.

An advantage of the present device resides in the apparent lack of noise during its operation and, further, upon the fact that as the condensing point of the plugger is pressed against the filling 50 material, the patient is not conscious of any pounding or hammering action. For this reason the device is advantageous due to its physiological principle; the force of all blows is substantially definite in the direction of line of activity; mechanically perfect control in the packing of the 55 filling material may be maintained; and aesthetically and hygienically the device is sanitary and efficient.

The operation, uses and advantages of that 60 form of the invention shown in Figure 2 is as follows:

Assume first that the finger piece constituting the enlargement 27 is rotated so as to close the valve, to-wit, the valve 32 will be seated against its seat 25. The spring 55 will urge the valve 48 against its seat 51. The loose piston or hammer 65 16 is within the cylinder. If now the belt 12 is passed about the pulley of the dental engine, which dental engine may be under hand or foot 70 control, and the engine is actuated, the pulley 7 will be driven with the result that the piston 6 will be reciprocated within the cylinder 5. However, the piston 16 will not be moved. Upon opening the valve 32, during operation of the pump, 75 conditions of pressure and rarefaction will occur

within the cylinder but not sufficient to cause the piston to perform work, for the reason that that side of the cylinder on the opposite end of the piston is closed to the atmosphere. However, when pressure is exerted upon the condensing point 57 of the plugger, the plugger will be moved inwardly, which inward movement will be communicated through the chuck and stem to the valve moving the valve from its seat. Communication may be had between one end of the piston and the atmosphere through the ports 40 and 41 and the screw-threaded bore 15. Obviously the amount of opening of the valve will determine the area of the passageway so far as the valve and its seat are concerned, the other passageways being fixed as to area. Thus, pressure upon the plugger may open the valve to a selected extent, with the result that air pressure forward of the piston may be relieved to the atmosphere. Obviously, this will allow the hammer or piston to move more rapidly and to strike a harder blow against the face of the valve which serves a dual purpose as valve and anvil. It has been found that when the device must be used for packing or driving filling in such a manner that the said device must be held substantially vertically that the spring 59 functions in urging the piston in one direction. Turning movement of the plugger is prevented due to the method of co-engagement between the plugger and the stem, together with the pinned relationship that exists between the nose and the valve disc.

The operation of that form of the invention illustrated in Figure 3 is identical with that of Figure 2, with the possible exception that the stem and the shank of the plugger includes therebetween the two balls 79 and 80. Pressure upon the condensing point of the plugger will be communicated through the two balls to the stem to open the valve, the coil spring 81 normally urging the valve to seated position.

The pluggers in either form of the invention may be readily removed and other forms of pluggers placed in position of service.

It is obvious that various changes and modifications and variations may be made in practicing the invention in departure from the particular showing of the drawing without, however, departing from the true spirit of the invention.

I claim:

1. A pneumatic mallet comprising a hand piece, a free piston arranged to reciprocate in said hand piece, means for supplying by a closed flow line connected with one end of the hand piece a confined pulsating fluid pressure to the power end of the piston, a throttle valve controlling the flow in said closed flow line to vary the striking force of the piston, a plugger assembly in the other end of the hand piece engageable by the piston when the same is reciprocated, and means to connect or disconnect the striking face of the piston with the atmosphere to control the operation of the mallet.

2. A pneumatic mallet comprising a hand piece, a free piston arranged to reciprocate in said hand piece, means for supplying a confined pulsating fluid pressure to the power end of the piston including a valve assembly comprising two valve members, one of said valve members being removably fitted in one end of said hand piece and provided with a bore and formed with a valve seat, the other valve member being connected with the fluid pressure supply and formed with a shank screw seated in the bore of said first valve member and provided with a bore extending from its 75

outer end to a point near its inner end, and provided with ports extended from the inner end of said shank bore through the sides of said shank to the bore of said first valve member, a valve 5 on the inner end of said shank for coacting with said valve seat for controlling the flow of fluid through said valve members, a plugger assembly in the other end of the hand piece engageable by the piston when the same is reciprocated, and 10 means to connect or disconnect the striking face of the piston with the atmosphere to control the operation of the mallet.

3. A pneumatic mallet comprising a hand piece, a free piston arranged to reciprocate in said hand 15 piece, means for supplying a confined pulsating fluid pressure to the power end of the piston including a valve assembly comprising two valve members, one of said valve members being removably fitted in one end of the hand piece and 20 provided with a bore and formed with a valve seat, the other valve member being connected

with the fluid pressure supply and formed with a shank screw seated in the bore of said first valve member and provided with a bore extending from its outer end to a point near its inner end, and provided with ports extending from the inner 5 end of said shank bore through the sides of said shank to the bore of said first valve member, a valve on the inner end of said shank for coacting with said valve seat for controlling the flow of fluid through said valve members, an anvil valve 10 reciprocatively mounted in the other end of said hand piece in the path of movement of said piston, a stem connected to said anvil valve, a chuck connected to said stem, a plugger mounted in said chuck, a spring for normally holding said anvil valve against its seat, and means for controlling the admission of the atmosphere to the striking 15 end of the piston when pressure is applied to the outer end of said plugger and said anvil valve is moved away from its seat.

GEORGE M. HOLLENBACK.
